OPHTHALMIC MOUNTINGS

Armand De Angelis, Southbridge, Edmund Donald Hoyt, Auburn, and Norman S. Di Lorenzo, Southbridge, Mass., assignors to American Optical Company, Southbridge, Mass., a voluntary association of Massachusetts

Application January 7, 1954, Serial No. 402,736

5 Claims. (Cl. 38—41)

This invention relates to improvements in ophthalmic mountings and has particular reference to the provision of a mounting embodying a main lens supporting structure having combined metallic and non-metallic parts interchangeably related with each other.

One of the principal objects of the invention is to provide a main adjustable lens supporting structure of metal which may be adjusted to the requirements of different individuals and non-metallic trims of controlled different contour shapes and colors which may be removably and interchangeably attached to the metallic supporting structure to alter the general appearance thereof with a view to obtaining different esthetical effects and a more pleasing blend of the mounting with the apparel to be worn with said mounting.

Another object is to provide a main metallic supporting structure and interchangeable decorative trims of different contour shapes and colors for use with said structure, each of said trims having integrally related connection means shaped to interfit with integral portions of said structure in such manner that the trims will be firmly held on said structure without the requirement of additional separate connection means.

Another object is to provide a mounting of the above character which is so constructed that the lenses may be removed from or placed in the lens supporting rims of the mounting without having to disconnect and remove the detachable trims.

Another object is to provide a metallic mounting which is complete as to design and structure and a plurality of trims of different contour shapes and colors so formed as to be detachably connected with the mounting and which may be furnished in the form of a kit whereby the said mounting is capable of use either with or without said trims.

Another object is to provide a novel construction of detachable trim mounting wherein the trims do not conceal the bridge and endpieces of the main lens supporting structure of the mounting when positioned thereon.

Another object is to provide a lens supporting frame of metallic material embodying a pair of lens rims joined nasally by a bridge member and having temple endpieces with separable portions extending outwardly of the temporal sides thereof, one of said separable portions having a lip extending rearwardly of the other of said portions, and decorative trims each having an intermediate portion channeled on the underside thereof to receive the upper portion of the rims between the bridge and endpieces and having opposed depending end portions notched inwardly of a side surface thereof, one of said notches being shaped to receive an end of the bridge and having a lower portion channeled inwardly in a direction substantially normal to the notch to receive a portion of the rim beneath the bridge and the other of said notches being shaped to receive the rearwardly extending lip with the lower wall of the notched portion functioning as a latch extending beneath said lip, the side wall of the intermediate channeled portion overlying the rim on the side of the trim

opposed to the bases of the notched portions being adapted to function cooperatively to retain the trim in position on the supporting structure.

Other objects and advantages of the invention will become apparent from the following description taken in conjunction with the accompanying drawings, and it will be apparent that many changes may be made in the details of construction and arrangement of parts shown and described without departing from the spirit of the invention as expressed in the accompanying claims. We, therefore, do not wish to be limited to the exact details of construction and arrangement of parts shown and described as the preferred form only has been given by way of illustration.

15 Referring to the drawings:

Fig. 1 is a front elevational view of an ophthalmic mounting embodying the invention;

Fig. 2 is a plan view of the mounting shown in Fig. 1;

Fig. 3 is a side elevational view of the mounting;

20 Fig. 4 is a fragmentary bottom plan view of one of the temple endpieces of the mounting;

Fig. 5 is an enlarged front perspective view of one of the decorative trims looking from the nasal side toward the inner temporal side;

25 Fig. 6 is a view generally similar to Fig. 5 looking from the temporal side into the inner nasal side of the trim;

Fig. 7 is an enlarged sectional view taken as on line 7—7 of Fig. 1 and looking in the direction indicated by the arrows;

30 Fig. 8 is an enlarged fragmentary sectional view taken as on line 8—8 of Fig. 1 and looking in the direction indicated by the arrows;

Fig. 9 is an enlarged fragmentary sectional view taken as on line 9—9 of Fig. 1 and looking in the direction indicated by the arrows; and

35 Fig. 10 is a fragmentary exploded rear perspective view of the temporal side of the mounting.

Referring more particularly to the drawings wherein like characters of reference designate like parts throughout the several views, the main metallic frame comprises a pair of lens rims 11 beveled inwardly to receive the lenses 12. The nasal sides of the rims 11 are joined by a bridge member 13 having outwardly tapering wedge-shaped end portions 14. The widest ends 15 of said wedge-shaped portions are secured to the front side surface of the rims by solder or the like. Secured to the temporal sides of the rims, as by solder or the like, and extending outwardly thereof are endpieces 16. One of said endpieces and an adjacent portion of the rims each having a front wedge-shaped shield-like portion 17 secured thereto by solder or the like is illustrated at 18. The endpieces 16 are each provided with a hinge connection 19 to which temples 20 are pivotally connected in conventional manner. The endpieces 16 each comprise an upper relatively wide portion 21 and a relatively narrow lower portion 22 adapted to abut each other and having aligned openings therein for receiving an attachment screw 23, see Fig. 9. The opening in the upper portion 21 is threaded to receive the threaded portion 24 of the screw while the lower portion 22 has a shouldered recess therein for receiving the head of the screw. The upper portion 21 extends outwardly as illustrated at 25 to provide a shelf or lip rearwardly of the lower portion 22.

65 The nasal sides of the rims 11 are provided with rearwardly extending nose pad supporting arms 26 which are secured thereto by soldering or the like and to which suitable nose pads 27 may be pivotally or rigidly attached as indicated at 28. This arrangement provides a main metallic lens supporting structure which is complete in itself and which may be worn as is. However, the tapered ends 14 of the bridge, upper portions of the

rims and the endpieces are so constructed that detachable non-metallic decorative trims 29 may be attached thereto if desired.

Although only one shape of trim is shown and described, it is to be understood that many trims of different contour shapes and colors are to be provided in accordance with the invention. Each trim 29, however, is controlled dimensionally and structurally to fit properly with the ends 14 of the bridge, the upper portions of the rims and the endpieces and to assume a positive assembled relation therewith.

Each trim 29 is provided, in a side surface of the nasal end thereof, with a notch 30 having upper and lower side walls 31 and 32 shaped to straddle a tapered end portion 14 of the bridge and to have a relatively intimate fit therewith. Each trim 29, beneath the notch 30, has a depending portion 33 formed with a channel 34 disposed in substantially normal relation with the notch 30 and adapted to fit about a section of the rim 11 directly beneath the tapered end 14. The channel 34 blends into a channel 35 formed in and throughout the length of the undersurface of the trim 29. The channel 35 is shaped to and is adapted to intimately receive the upper section of the rim 11. The channel 35 communicates with a notch 36 formed in the temporal end of the trim 29 and which has its base 37 disposed in a plane spaced rearwardly of the plane of the rear side wall 38 of the channel 35, see Figs. 5 and 6. To enable this to be accomplished the temporal end of the trim 29 is provided with a rearwardly extending portion 39 in which the notch 36 is formed. The notch 36, when the trim 29 is in fitted position upon the upper portion of the rim 11, is adapted to fit about the rearwardly extending shelf or lip 25 with the upper side wall 40 and the lower side wall 41 thereof in relatively intimate relation therewith and with the base 37 of the notch fitting relatively intimately with the rear edge surface of said shelf or lip 25. The portion having the lower side wall 41 forms a latch to secure the trim to the top of the mounting.

The front free edge surface 42 of the portion of the trim beneath the shelf or lip 25 lies slightly rearwardly of the rear wall 38 of the channel 35 and provides a space between said front edge surface 42 and the rear surface of the shield-like portion 17 in which the lower portion 22 of the endpiece may be fitted in intimate relation with the upper portion 21 of said endpiece. This arrangement permits the screw 23 to be loosened and the endpiece portion 22 to be withdrawn from the endpiece portion 21 an amount sufficient to permit interchanging of lenses without requiring the detachment of the trim 29 from the main metallic supporting structure, as shown best in Figs. 9 and 10.

The channel 35 is controlled dimensionally to have its side walls 43 and 44 fit in relatively intimate relation with the front and rear edge surfaces of the rim 11 and to have the base 45 of said channel fit in relatively intimate relation with the outer edge surface of the upper rim section 11 to substantially conceal said rim section in said channel.

The temporal end of the trim 29 is cut away, as illustrated at 46, to provide clearance of the upper edge of the shield-like portion 17 and to have a contour shape which follows substantially the upper edge shape of said shield-like portion.

It is further pointed out that the upper inner wall 31 of the notch 30 lies substantially in the plane of the base 45 of the channel 35 and the front wall of the channel has an edge 47 curving upwardly and outwardly to blend with said inner wall.

It is further pointed out that the said upper and lower wall portions 31 and 32 are shaped to the contour shape of the upper and lower edges of the end portions 14 of the bridge 13 and to have a relatively intimate fit therewith.

The trims 29 are placed in assembled relation with the mounting by first fitting the notched portion 30 of a trim about an end portion 14 of the bridge and drawing the end 33 and channeled portion 34 inwardly in overlying relation with the portion of the rim directly beneath said portion 14. The upper intermediate portion of the trim 29 is then forced downwardly in overlying relation with the intermediate upper portion of the rim 11. The temporal end of the trim having the notch 36 therein is then fitted over the rearwardly extending lip 25 and is pressed downwardly and inwardly to cause the latch portion formed by the lower wall 41 to snap beneath the lip 25 to lock the trim on the mounting.

It is particularly pointed out that when the trim 29 is in fitted position on the mounting with the front wall 43 of the channel 35 engaging the front edge surface of the rim section and with the bases of the notches 30 and 36 overlying the respective rear surfaces of the bridge and lip 25 the said front wall and bases of said notches will function cooperatively to retain the forwardly extending end 33 and the forwardly extending end 42 in latched position beneath said bridge and lip. This is in response to the inherent resilient characteristics of the non-metallic material from which the trims 29 are formed. To further aid in retaining the nasal end of the trim on the mounting, the lower end 33 is provided with an inner channel 34 which overlies the section of the rim directly beneath the bridge. This prevents the end portion having the notch 30 therein from being free to move rearwardly relative to the bridge and more positively retains the said end in attached relation with the bridge. The intimate fit of the channel 35 with the upper section of the rim further aids in positively retaining the trim in assembled relation with the mounting.

The shields 17 are secured by solder or the like only to the upper portions 21 of the endpieces whereby the lower relatively narrow portions 22 are free to move outwardly away from said upper portions 21 when the screws 23 are loosened.

To detach the trims all that is necessary is to push the end portion 42 rearwardly clear of the shelf or lip 25 where the remainder of the trim may be easily pulled up and removed from the mounting.

It is pointed out that the outer contour of the trims may be varied as desired, that is, the outer shapes of the trims intermediate the notched portions without interfering with the fit of the trims with the mounting provided that the undersurface of the trims is retained to the contour shape of the rims and that the channel in said undersurface and the general detailed construction of the notches in the nasal and temporal ends of the trims are held dimensionally and structurally constant. With this arrangement trims of many different contour shapes and colors may be provided and selected as desired for assembly with the main lens supporting structure of the mounting and when attached thereto will retain a snug and positive fit therewith.

It is further pointed out that the trims, as shown in Figs. 1, 5 and 6, have their opposed ends 48 and 49 tapering outwardly to relatively thin edges 50 and 51 whereby the said ends, when in attached relation with the main lens supporting structure, will have a pleasing blend into the adjacent upper edge surfaces of the bridge and shield-like portions 17.

Although the main lens supporting structure has been shown and described as having lens rims which surround the entire contour of the lenses, it is to be understood that a lens supporting structure having only semi-rim portions may be employed if desired, that is, a structure having in effect the lower portions of the rims removed as is common in present-day semi-rim structures. In this instance, however, the bridge, upper rim portions and temple endpieces will have a structure identical to that of the mounting described above with the exception that

the upper and lower portions of the endpiece would not of necessity have to be divided and connected by a screw such as is required with the continuous rims. The rims, however, on the nasal sides thereof have portions extending slightly downwardly below the ends of the bridge to provide means with which the ends 33 having the inner channels 34 therein may be latched. In all other respects the upper structure of the semi-rim mounting and trims would be similar to the upper structure and trims of the mounting described herein.

From the foregoing description it will be seen that simple, efficient and economical means have been provided to accomplish all of the objects and advantages of the invention.

Having described our invention we claim:

1. An ophthalmic mounting comprising a pair of lenses, a central bridge and a pair of lens rims on opposed sides thereof in which the lenses are mounted, each of said lens rims having a nasal portion secured to an end of said bridge, a temple hinge bearing member secured to a temporal portion of each lens rim and having a sidewise disposed shelf thereon, and a pair of separate readily detachable snap-on trims each having a channel on their underside to receive the upper portion of the mounting between the temple hinge bearing member and the end of the bridge attached to said lens rim, said trims each terminating in a nasal depending portion which extends along the nasal contour of the lens rim a distance below the end of the bridge, said nasal depending portion having a slot in a side surface thereof at a location above the lowermost extension of said depending portion and communicating with said channel, said slot being so located and of a shape to receive and leave exposed the major portion of the attached end of the bridge, and the remaining part of said nasal depending portion extending below said slot having a continuation of said channel and providing a lip which extends towards and partially encircles the nasal part of the lens rim below said attached end of the bridge to catch therewith, and the temporal end of said trims each terminating in an end part which overlies, in approximately flush relation therewith, the top surface of the temple hinge bearing member leaving a major portion of the side surface of said temple hinge bearing member exposed, said temporal end further having a depending portion which depends to one side of the temple hinge bearing member and terminates in a sidewise disposed lip which may be forced under the sidewise disposed shelf of the temple hinge bearing member to frictionally and releasably hold the trim in place when the slot in said nasal portion of the trim is located on the attached end of the bridge and the lip on the nasal depending portion of the trim is caught about a nasal portion of the lens rims.

2. A lens supporting structure embodying a central bridge and a pair of encircling lens rims on opposed sides thereof each having a nasal portion secured to an end of said bridge, said lens rims being divided on their temporal side, a temple hinge bearing member secured to the upper one of said divided ends and extending outwardly therefrom, a lug secured to the other of said divided ends and adapted to be detachably connected to the temple hinge bearing member to releasably hold lenses in place in the lens rims, said temple hinge bearing member having a part extending outwardly to one side of the extent of the lug to serve as a catch, and a pair of separate readily detachable snap-on trims each having a channel on their underside to receive the upper section of a respective lens rim between the temple hinge bearing member and the end of the bridge attached to said lens rim, said trims each terminating in a nasal depending portion which extends along the nasal contour of the lens rim a distance below the end of the bridge, said nasal depending portion having a slot in a side surface thereof at a location above the lowermost extension of said depend-

ing portion and communicating with said channel, said slot being so located and of a shape to receive said attached end of the bridge and leave the major portion of a side surface thereof exposed and the remaining part of 5 said nasal depending portion extending below said slot having a continuation of said channel and providing a lip which extends towards and partially encircles the nasal part of the lens rim below said attached end of the bridge to catch therewith, and the temporal end of said trims 10 terminating in an end part which overlies, in approximately flush relation therewith, the top surface of the temple hinge bearing member leaving the major portion of a side surface of said temple hinge bearing member exposed, said temporal end further having a depending portion 15 which depends along one side of said temple hinge bearing member and terminates in a sidewise disposed lip which may be forced under the mentioned catch formed on the temple hinge bearing member to frictionally and releasably hold the trim in place when the 20 attached end of the bridge is in the slot provided therefor in the side surface of the nasal depending portion of the trim and the lip below said slot is assembled with the nasal part of the rim, and said sidewise disposed lip on the temporal side of the trim being so dimensioned as to 25 obtain its function while being sufficiently spaced from the lug to permit separation and attachment of said lug with the temple hinge bearing member so as to allow the ready removal and insertion of lenses in the lens rims without removal of the trims.

3. A lens supporting structure embodying a central bridge and a pair of encircling lens rims on opposed sides thereof each having a nasal portion secured to an end of said bridge, said lens rims being divided on their temporal side, a temple hinge bearing member secured to the upper one of said divided ends and extending outwardly therefrom, a perforated lug secured to the other of said divided ends and aligned beneath only a portion of said temple hinge bearing member, said temple hinge bearing member having a threaded aperture in alignment with the perforation in said lug by means of which a screw extended through the perforation in the lug may be threadedly connected to the temple hinge bearing member to hold lenses in place in the lens rims, said temple hinge bearing member having a part extending rearwardly of the extent of the lug to serve as a catch, and a pair of separate readily detachable snap-on trims each having a channel on their underside to receive the upper section of a respective lens rim between the temple hinge bearing member and the end of the bridge attached to said lens rim, said trims each terminating in a nasal depending portion which extends along the nasal contour of the lens rim a substantial distance below the end of the bridge, said nasal depending portion having a slot 40 extending inwardly of the front side surface thereof at a location above the lowermost extension of said depending portion and communicating with said channel, said slot being so located and of a shape to receive and leave exposed the front surface of the attached end of the bridge, 45 and the remaining part of said nasal depending portion extending below said slot having a continuation of said channel and providing a lip on the forward side thereof extending toward and which catches with the nasal part of the lens rim below said attached end of the bridge, 50 and the temporal end of said trims terminating in an end part which overlies, in approximately flush relation therewith, the top surface of the temple hinge bearing member leaving the major portion of the front surface of said temple hinge bearing member exposed, said temporal end further having a depending portion on its rear side which, with respect to the general plane of the channel in said trim, is disposed substantially entirely rearwardly thereof, said depending portion having a slot in its forward surface shaped to receive the catch formed on 55 the temple hinge bearing member and to provide a for-

wardly extending lip which, by reason of the inherent resiliency of the material of the trim, may be forced under the mentioned catch formed on the temple hinge bearing member to frictionally and releasably hold the trim in place when the slot extending inwardly of the front side of the nasal depending portion of the trim is in position on the attached end of the bridge and the lip on the nasal depending portion of the trim catches with a nasal portion of the lens rims, and said forwardly extending lip on the temporal side of the trim being so dimensioned as to obtain said function while being sufficiently spaced from the perforated lug to permit, on loosening of the mentioned screw, separation and attachment of said perforated lug to the temple hinge bearing member to permit ready removal and insertion of lenses in the lens rims without removal of the trims.

4. A lens supporting structure embodying a central bridge, a pair of encircling lens rims on opposed sides thereof each having a nasal portion secured to an end of said bridge, nose bearing means secured to said lens rims on their nasal sides at a point spaced below said securing of the end of the bridge with the lens rims, said lens rims being divided on their temporal side, a temple hinge bearing member secured to the upper one of said divided ends, a perforated lug secured to the other of said divided ends, said temple hinge bearing member having a threaded aperture in alignment with the perforation in said lug, a screw extendable through the perforation in the lug and threadedly connectable into the aperture of the temple hinge bearing member to releasably retain lenses within said lens rims, said temple hinge bearing member having a part extending rearwardly of the extent of the lug to serve as a catch, and a pair of separate readily detachable snap-on trims of inherently resili-ent plastic material each having a channel extending longitudinally on their underside to receive the upper section of a respective lens rim between the temple hinge bearing member and the end of the bridge attached to said lens rim, said trims each terminating in a nasal depending portion which extends to a point between the end of the bridge and where the nose bearing means is secured to the lens rim, said nasal depending portion having a slot in the front side surface thereof communicating with said channel, said slot being of a shape to receive and leave exposed the major portion of the front side surface of the attached end of the bridge, and the remaining part of said nasal depending portion below said slot having a continuation of said channel to provide a lip on the forward side thereof which extends towards and partially encircles the nasal part of the lens rim between the end of the bridge and attachment of the nose bearing means to catch therewith, and the temporal end of said trims terminating in an end part which overlies the top surface of the temple hinge bearing member and further has a depending portion which is disposed rearwardly of the temple hinge bearing member and terminates in a forwardly extending lip which may by the inherent resiliency of the material of the trim be forced under the catch formed on the temple hinge bearing member to frictionally and releasably hold the trim in place when the slot extending inwardly of the front side of the nasal depending portion of the trim is in position on the attached end

of the bridge and the lip on the nasal depending portion of the trim is caught with a nasal portion of the lens rims, and said forwardly extending lip being so dimensioned as to obtain said function while being sufficiently spaced from the perforated lug to permit, on loosening of the mentioned screw, separation and attachment of said perforated lug to the temple hinge bearing member to permit ready removal and insertion of lenses in the lens rims without removal of the trims.

5. A readily detachable snap-on type decorative trim for a lens supporting structure of an ophthalmic mounting which is characterized by a pair of encircling lens rims each having a nasal portion secured to an end of an intermediate bridge and having temple hinge bearing members secured to temporal portions thereof, said decorative trim comprising a relatively long and slender member provided with a channel in its underside to receive the upper section of a respective lens rim between the temple hinge bearing member and the end of the bridge attached to said lens rim, said trim terminating in a nasal depending portion which is shaped to extend along the nasal contour of the lens rim a substantial distance below the end of the bridge, said nasal depending portion having a slot in the front side surface thereof at a location above the lowermost extension of said depending portion and communicating with said channel, said slot being so located and of a shape to receive and leave exposed the major portion of the front surface of the attached end of the bridge, and the remaining part of said nasal depending portion extending below said slot having a continuation of said channel and providing a lip which is shaped to extend toward and which will partially encircle the nasal part of the lens rim below said attached end of the bridge to catch therewith, and the temporal end of said trim terminating in an end part which will overlie the top surface of the temple hinge bearing member leaving the major portion of the front surface of said temple hinge bearing member exposed, said temporal end further having a depending portion on its rear side which, with respect to the general plane of the channel in said trim, is disposed substantially entirely rearwardly thereof, said depending portion having a slot in its forward surface shaped to receive a portion of the temple hinge bearing member and so provide a forwardly extending lip which, by reason of the inherent resiliency of the material of the trim, may be forced under said portion of the temple hinge bearing member to frictionally and releasably hold the trim in place on a respective lens rim when the slot extending inwardly of the front side of the nasal depending portion of the trim is in position on the attached end of the bridge and the lip on the nasal depending portion of the trim is caught with a nasal portion of the lens rims.
